AMUSEMENT DEVICE

Wayland D. Keith, Wichita Falls, and Ronald W. Walker, Megargel, Tex.; said Walker assignor to said Keith

Application November 4, 1935, Serial No. 48,244

21 Claims. (Cl. 272—36)

The invention is primarily designed to provide entertaining apparatus of the riding car type in which the passenger is enabled to control the movements of the car within certain limitations to attain thrills and emotions out of the ordinary and not possible with mechanism having a predetermined movement.

In accordance with the invention the cars are pivotally mounted to travel in a variety of paths and each may be equipped with a power unit and passenger control whereby the occupant may obtain independent movement and experience a sensation and emotion not obtainable by devices of the nature aforesaid as ordinarily provided.

In general, the present invention embodies a pole, arms mounted on the pole and adapted to receive a twofold movement, the one to revolve about the pole as an axis, and the other to turn about an axis perpendicular to the axis of the pole, cars pivoted to the outer ends of the arms to normally maintain a given relative position, a power unit and passenger control for attaining an independent movement within the range of and capability of the car.

While the drawings illustrate a preferred embodiment of the invention, it is to be understood that in adapting the same to meet specific needs and requirements, the design may be varied and changes in the minor details of construction may be resorted to within the scope of the invention as claimed, without departing from the spirit thereof.

For a full understanding of the invention and the merits thereof, reference is to be had to the following description and the drawings hereto attached, in which:

Figure 1 is a side elevation of an embodiment of the invention, the base being in section and parts broken away.

Figure 2 is a top plan view, the guys being omitted.

Figure 3 is a front view similar to Figure 1.

Figure 4 is an enlarged view on the line 4—4 of Figure 3.

Figure 5 is an enlarged detail perspective view on the line 5—5 of Figure 3.

Figure 6 is a detail sectional view on the line 6—6 of Figure 3, showing the parts on a larger scale.

Figure 7 is a detail sectional view on the line 7—7 of Figure 1, showing arrangement of bearings in arm and in car.

Corresponding and like parts are referred to in the following description and designated in the

several views of the drawings by like reference characters.

The machine, as shown, consists of a pole embodying sections 10—10a flanged and bolted at their abutting ends and strengthened by trussed braces 10b. A hollow base 9 receives the lower end of the pole and guys 36 extend from a bearing 35 fitted to the upper end of the pole. A mount 21a within the base 9 is surmounted by a bearing 21 journaling the pole. A worm gear 17 is connected to the pole and a worm 18 is in mesh therewith and is driven by a motor 19. A brake drum 20a (see Fig. 6) fast upon the pole has a brake band 20 in cooperation therewith. A pedal 20d mounted upon the base 9 is connected by link 20c with lever 20b to which the ends of the brake band 20 are connected.

A horizontal shaft 13 is mounted intermediate its ends in the pole section 10a and has a pair of arms 11 secured to each end thereof. A gear 20 wheel 16 on the shaft 13 and fast thereto is in mesh with a pinion 15 secured to the shaft of an electric motor 14 mounted on the pole. A brake 28, similar to the brake 20—20a is associated with the shaft 13 and is electrically operated by an electromagnet 27 and lever 29. The arms 11 of each pair are parallel and diagonally braced and pivotally support cars 12 between their adjacent outer ends. The cars 12 may be of any design and are pivotally journaled at 12c (Fig. 7) on transverse shafts 12b, which shafts 12b are journaled in bearings 11a in the arms 11. An electric motor 38 may be associated with each of the cars and is mounted on the inner one of the arms 11. A worm 40 on the motor armature shaft is in mesh with a worm gear 40a fixed to the shaft 12b. In consequence, when the motor 38 is running, the shaft 12b is rotated and turns the brake drum 42 attached thereto forming a clutch on said shaft, as shown in Fig. 4. A brake 40 coacts with each of the cars 12 and consists of a drum 42 keyed at 43 to the shaft and a brake band 41 attached at its ends to a lever 44 connected by a link with an arm 44a fixed to a shaft journaled in the car 12, which shaft carries a lever, the opposite ends of which are connected with pedals 45, readily accessible to the occupants of the car on seats 46, and when pressed upon, either of these pedals applies the brake 41 and holds the car in a fixed relation to shaft 12b. If brake 41 is applied while shaft 12b is being rotated by motor 38 car 12 will be rotated, and if said brake is applied while motor 38 is not running car 12 will be held in fixed relation to shaft 12b and arms 11, relative rotation being pre-

vented by worm 40 and worm gear 40a. The motors 38 are included in circuits having switches 39a that may be conveniently positioned to be readily operated by the passenger of a car. These 5 circuits also include ring contacts 30 secured by blocks 30a to the innermost arms 11, and having cooperating brushes 37 as indicated in Figure 5 of the drawings.

The circuit, with the exception of motor 19, 10 has ring contacts 31 and cooperating brushes 32, the rings 31 being held by blocks 31a secured to the pole section 10a as shown to advantage in Figures 1, 3, and 6. The various circuits are 15 designated by the numeral 23a and are shown diagrammatically in the drawings but will be evident to one skilled in the art, and include switches, indicated at 22, 23, 24, 25, and 26 to admit of starting and stopping the several electrically actuated operating parts. The hollow base 20 9 is utilized as a housing for the motor 19, switches 22 to 26, ring contacts 31, brushes 32, worm gearing 17-18 and brake 20, the top boards of the base serving as a loading platform.

When the motor 19 is running, the pole turns 25 about a vertical axis and causes the arms 11 and cars 12 to revolve in a horizontal plane. Upon starting the motor 14, the horizontal shaft 13 is rotated and revolves the arms 11 and the cars 12, which are pivotally mounted on the arms 11 in 30 vertical planes. Under normal conditions the cars 12 maintain a level position. By applying the brake 41 the car is held fast to the shaft 12b and moves therewith when said shaft is rotated by motor 38 as indicated at 12a in Fig. 1, producing a thrill due to the travel of the car in a 35 circular path. By alternately applying and releasing the brake 41 the car receives a swinging movement in addition to the orbital travel, producing an additional excitement. By starting the motor 38 the shaft 12b is rotated freely in 40 bearings 12c with no effect on rotation of the car until brake 41 is applied, and by applying the brake 41 the car will be held fast to the shaft 12b and rotated therewith. Thus the car and passenger receive a three-fold movement, one about the shaft 12b, the other around the shaft 13, and the third in a horizontal plane about the pole 10 as an axis. The additional thrills are 45 under control of the passenger through the instrumentalities associated with the brake and the motor, as will be readily appreciated.

Having thus described the invention, what is 50 claimed is:

1. An amusement device comprising a vertical standard, a horizontal shaft mounted intermediate the ends of the standard, driving means for turning said standard, independent driving means on the standard for rotating the horizontal shaft, supports fixed to said horizontal shaft, passenger cars pivotally mounted on said supports, a bearing mounting a lower portion of said standard, a second bearing mounted on the upper portion of the standard above the horizontal shaft, and guying means connected with the upper bearing.
2. An amusement device of the character specified comprising a vertical standard, a horizontal shaft mounted on the standard intermediate the ends of said standard, driving means for turning the standard, independent driving means on the standard for rotating the horizontal shaft, supports fixed to said horizontal shaft, passenger cars pivotally mounted on said supports and having braking means associated therewith in position for operation by passengers in the cars, a bearing mounted on an upper portion of said standard,

and guying means above the horizontal shaft and connected with the upper bearing.

3. An amusement device of the character specified comprising a vertical standard, a horizontal shaft mounted on the standard intermediate the ends of said standard, driving means for turning the standard, independent driving means on the standard for rotating the horizontal shaft, supports on said horizontal shaft, passenger cars pivotally mounted upon said supports, said supports having motors for rotating said cars on their respective axes, a bearing mounting the lower portions of said standard, a second bearing mounted on the upper portion of the standard above the horizontal shaft, and guying means associated with the upper bearing. 15

4. In an amusement device of the character specified, supporting means mounted to turn about a vertical and a horizontal axis, a car pivotally mounted on said supporting means, a power unit carried by the supporting means for imparting an independent rotary movement to the car, manually operated holding means for securing the car to the support to prevent independent movement, a control on the car for actuating the manually operated holding means and for causing turning movement of the car by the power unit. 20

5. In an amusement device of the character specified, supporting means mounted to turn about a vertical and a horizontal axis, a car pivotally mounted on said supporting means, a power unit carried by the supporting means for imparting an independent rotary movement to the car, and a control on the car for the power unit and operable by a passenger. 30

6. In an amusement device of the character specified, a support mounted to turn about a vertical and a horizontal axis, a car pivotally mounted on said support, a power unit for imparting an independent rotary movement to the car, holding means for securing the car to the support to prevent independent movement, and a control on the car for the holding means to secure the car or effect release thereof to admit of free pivotal movement. 45

7. An amusement device comprising a pole, a horizontal shaft mounted intermediate its ends on the pole, driving means for turning the pole, independent driving means on the pole for rotating the shaft, a brake mounted on said horizontal shaft, means for controlling said brake and independent driving means from a remote point, passenger cars, supports pivotally mounting the cars on said horizontal shaft, and passenger controlled means for imparting an independent movement to the cars. 50

8. An amusement device comprising a pole, a horizontal shaft mounted intermediate its ends on the pole, driving means for turning the pole, independent driving means on the pole for rotating the shaft, passenger cars, supports fixed on the horizontal shaft and pivotally mounting the cars, driving means on the supports for imparting an independent rotary movement to the cars, and passenger controlled means for throwing the driving means into and out of action. 60

9. An amusement device comprising a pole, a horizontal shaft mounted intermediate its ends on the pole, driving means for turning the pole, independent driving means on the pole for rotating the horizontal shaft, passenger cars, supports fixed on the horizontal shaft and pivotally mounting the cars, driving means on the supports for imparting an independent movement to the respective cars, passenger controlled 70

means for throwing the driving means into and out of action, manually operable holding means for securing the cars to the supports, and passenger controlled means for releasing and throwing 5 the holding means into action.

10. An amusement device comprising a pole, a horizontal shaft mounted intermediate its ends on the pole, driving means for turning the pole, independent driving means on the pole for rotating the shaft, arms fixed to the ends of the horizontal shaft, transverse shafts loosely mounted in the outer ends of the arms, cars loosely mounted on the transverse shafts, driving means on the arms for rotating the respective transverse shafts, a brake for each of the transverse shafts, means under control of the passenger for throwing the driving means into and out of action, and passenger controlled means for setting and releasing the brake as desired. 15

20. 11. An amusement device comprising a hollow base, a pole mounted therein, an electric motor in the base geared to the pole to effect turning thereof, a brake coacting with the pole and disposed within the base, a horizontal shaft mounted intermediate its ends on the pole, an electric motor mounted on the pole and geared to the horizontal shaft, an electrically operated brake mounted on the pole for controlling the movement of the horizontal shaft, arms fixed upon the ends of the horizontal shaft, transverse shafts mounted in the outer ends of said arms, cars pivotally mounted on the transverse shafts, an electric motor for each car geared to the supporting shaft thereof, passenger controlled means for the motor of each car, a brake for the transverse shaft of each car, and passenger controlled means for the brake. 25

12. In an amusement device of the character described, the combination of a central support, means for rotating said central support about a vertical axis, a transverse support journaled intermediate its ends on said central support, means for rotating said transverse support relative to the central support and independent of the rotary movement thereof, and passenger carrying means supported at opposite ends of the transverse support. 30

13. In an amusement device of the character described, the combination of a central support, means for rotating said central support about a vertical axis, a transverse support journaled on said vertical support and extending in opposite directions therefrom, means for rotating said transverse support independently of the central support and relative thereto, arms carried on opposite ends of said transverse support for rotation thereby, and cars journaled on said arms. 35

14. In an amusement device of the character described, the combination of a central support, means for rotating said central support about a vertical axis, a transverse support journaled on said central support and extending in opposite directions therefrom, means for rotating said transverse support independently of the central support and relative thereto, arms carried on opposite ends of said transverse support for rotation thereby, cars journaled in said arms, and means for securing said cars rigid with the arms for bodily rotation therewith, about the axis of the transverse support. 40

15. In an amusement device of the character described, the combination of a central support, means for rotating said central support about a vertical axis, a transverse support journaled in

termidate its ends on the central support and extending in opposite directions therefrom, means separate from and independent of the first-mentioned driving means for rotating the transverse support relative to the central support, car supporting means mounted on opposite ends of said transverse support, and cars journaled on said supporting means for swinging movement upon rotation thereof. 5

16. In an amusement device of the character described, the combination of a central support, means for rotating said central support about a vertical axis, a transverse support journaled intermediate its ends on the central support and extending in opposite directions therefrom, means separate from and independent of the first-mentioned driving means for rotating the transverse support relative to the central support, car supports mounted on opposite ends of said transverse support, cars journaled on said car supports for swinging movement upon rotation thereof, and means for rigidly fixing the cars to the car supports for bodily turning of said cars with said car supports. 10

17. In an amusement device of the character described, the combination of car supporting means, means mounting said car supporting means for rotation about a horizontal axis, a car journaled on the car supporting means for swinging movement about an axis extending approximately parallel with said horizontal axis, and frictional means for selectively securing said car rigidly to the car supporting means for bodily turning thereof with the car supporting means. 15

18. In an amusement device of the character described, the combination of car supporting means, means mounting said car supporting means for rotation respectively about vertical and horizontal axes, one or more cars journaled in the car supporting means, and frictional means for selectively securing the car or cars rigidly to the car supporting means for bodily turning movement therewith. 20

19. In an amusement device of the character described, the combination of car supporting means, means mounting said car supporting means for rotation respectively about vertical and horizontal axes, a car journaled on the car supporting means for swinging movement relative thereto about an axis extending approximately parallel with said horizontal axis, and frictional means having an operator within the car for selectively securing said car rigidly to the car supporting means for bodily turning movement thereof with the car supporting means. 25

20. In an amusement device of the character described, the combination of a vertical pole, means for turning said pole about a vertical axis, a transverse support, bearings spaced laterally from the pole and carrying the transverse support, and truss braces connected with opposite end portions of the pole and with the bearings. 30

21. In an amusement device of the character described, the combination of a vertical standard, means for rotating said standard, truss braces connected with opposite end portions of the standard and extending laterally therefrom at an intermediate portion, bearings carried by said truss braces and fixed thereto, and a transverse shaft journaled in said bearings. 35
